LEASE FORMING ATTACHMENT

William J. O'Connor, Dracut, Mass., assignor to
 Newmarket Manufacturing Company, Lowell,
 Mass., a corporation of Massachusetts

Application January 27, 1943, Serial No. 473,701

2 Claims. (Cl. 28—40)

This invention relates to means and machines for producing a lease in a warp and for fixing the lease of the threads before they are wound on the warp beam from which they are later drawn in or tied in in what is known as the "end to end" system.

This is accomplished generally on a machine known as a slasher and is known as setting up.

To form a warp having perhaps four thousand (4000) threads or ends on a warp beam, there may be four (4) thread rolls or section beams each with one thousand (1000) ends. The warp beam is positively driven but with a yielding motion and there may be produced from the four (4) thread rolls four or more finished warp beams.

As it is usually done, the four (4) sheets of threads from the four (4) thread rolls pass over separating rods and then through and between dents of a special type in a comb of a well known type, having a removable top but different from what is shown in the patent to Peterson, No. 1,605,277, of November 2, 1926. Four (4) threads, one from each roll, are in the space between each two dents and in one system all of the four thousand (4000) threads then pass over various rolls of the slasher and in some cases through a liquid bath and from thence to the warp beam proper.

The thread rolls or section beams are also provided with brakes or retarding means, the tension of each roll being so regulated that all the threads passing through the comb will have as nearly as possible the same tension.

Each thread roll or section beam can be unrolled or rolled back individually, but can be turned forward more easily than it can be turned back on account of the way its brake is made.

The purpose in general is to form a lease at one or both ends of each warp on the warp beam and to hold it in place by tapes which are passed through the sheds by means of lease rods or sticks which are then removed so that in some cases the taped warp can pass through the slasher or in other cases directly onto the warp beam.

In general, the method of forming a lease with threads alternating up and down and crossed is to form a shed in each sheet from a thread roll by manipulating it with a warp lifting lease rod in connection with the comb. The alternate dents of these combs have hooks so arranged that if a sheet of threads is moved up and transversely in one direction or the comb itself is moved oppositely, half the threads are caught while the

other half keep on going up with result that a shed is formed in that sheet.

The next sheet is lifted by its separating rod in the same way and moved transversely in the opposite direction and a second shed is formed. All the other sheets are treated in the same way with the result that a lease rod can be passed between the top and bottom separated threads beyond the comb to keep them separated. Ordinarily each separating rod with its sheet of threads is lifted and rested on a rack and the same proceeding is carried out with the next separating rod and sheet of threads from the next thread roll.

Eventually, with four (4) rolls, there will be four (4) sets of threads which I will call the top threads and four (4) more sets of threads which I will call the bottom threads which alternate with the top threads.

After passing a warp lifting lease rod between the top and bottom threads of the first shed, an opposite shed, to cross the threads and form a lease, is taken by reversing the process.

On the old system, there was a fixed lower rack with side arms which sloped from towards the thread rolls down towards the comb with a plurality of pairs of hooks or pins on which the warp lifting lease rods rested at the beginning of the operation, each with a sheet of threads from a thread roll passing over it.

There was another vertical upper rack with a series of pairs of hooks or rod holding pins and the proceeding was as follows:

The top rod was lifted by a man on each side and at the same time it was moved with the sheet of threads transversely of the sheet of threads in one direction, or the comb was moved, alternate threads catching in the hooks of the dents and forming a shed. This rod was placed on an upper pair of hooks of the upper rack.

The next rod with its sheet of warp was treated in a similar way, being moved transversely of the sheet of warp threads in the opposite direction, and was placed on a lower pair of hooks on the upper rack and then the third, etc., until all of the sheets of warp threads from the thread rolls had been separated, whereupon a lease rod was passed between the top threads and the bottom threads thus retaining the alternate crossed threads of the first shed in place.

To form a lease, it was now necessary to bring back the warp lifting lease rods to their original positions in the lower rack and this was done either by one man or by two men lifting the bottom rod from the lower hooks of the upper rack

and letting it down into its regular position on the lower rack and then doing the same thing successively with the other rods.

The objection to this was however that one or two men must turn back the thread roll on which each sheet was wound to take up the excess length of thread going over the rods in the upper rack. As the friction brake of each roll was so made as to permit a regulated tension on the unrolling movement, a great deal of effort was required in turning back this roll to take up the excess thread. Moreover, each thread roll must be turned back individually to bring the sheets of thread back to their first position of passing over the respective rods so that the cross lease could be taken by a similar sequence of movements to cause the top threads of the first shed to become the bottom threads of the second shed.

This invention is a means to more quickly take up the excess of thread over the rods in the upper rack and the provision of a movable upper rack of substantially the same character as the fixed lower rack having side arms just outside of the side arms of the fixed lower rack and which can be raised and held in the up position while the separating rods are lifted with their respective sheets of warp and placed in corresponding positions in this movable upper rack.

In the preferred form, I provide upper rack raising and lowering means which will allow the upper rack to be slowly lowered to a position outside the lower or fixed rack while the combined warp is being wound up onto the warp beam, thus taking up the slack or different lengths of thread between the various thread rolls and the comb according to the angle at which the sheets of the warp passed over the separating rods in the upper rack in its raised position. As this slack is taken up, all the thread rolls will turn forward, not back together. The slack of the sheet of thread going over the bottom rod will be taken up first but the others quickly follow.

This upper rack could be raised and lowered by a man on each side but preferably it is raised and lowered by mechanism which can be timed, controlled and synchronized with the winding up of the warp on the warp beam.

The advantages of my device and process are that they save much time and strength because, while the time of lifting each rod with its sheet of warp to form a shed is about the same as before, by lowering the top rack with all the rods together instead of lowering one rod at a time, I avoid the attendant delay of turning back each separate thread roll. As there may be three leases or six sheds for each warp made up on and removed from a warp beam, this may mean lifting a large number of lease rods for each of a substantial number of warps. The number of liftings of rods and their sheets of warps and of turning back the thread rolls may be very great.

Moreover, the thread beams are often so heavy that women are not strong enough to handle them and men must be employed to turn them back while with my device women or girls can easily do the lifting of the rods and sheets and there is no turning back of the thread rolls. On each slasher there is a saving of from ten to twenty per cent (10% to 20%) in the time required for leasing.

In the drawing,

Fig. 1 is a diagrammatic side elevation of the principal parts of a slasher of a well known type with my devices in place.

Fig. 2 is an isometric view of one side of the top rack and Fig. 3 of the rack lifting devices.

Fig. 2A is a view looking down from the top front on the two racks when they are together.

Fig. 4 is an elevation of a leasing comb and Fig. 5 is an enlarged diagrammatic section showing some of the dents of the comb and the movement of the threads.

Fig. 6 is a diagrammatic side elevation showing the sheets of warp after sheds have been taken in them.

In the drawing, A, A, A, A, represent four thread rolls each carried in suitable bearings such as 99 and each provided with a brake of the type having a band or rope 101 which passes over a pulley, or groove 103 forming part of a thread roll. It supports a weight 102 at one end and is fastened at 100 to the frame Z at its other end.

T, T, T, T, represent the sheets of warp threads which are wound on the various rolls A, A, A, A. These sheets of thread pass over warp lifting lease rods R1, R2, R3, R4, respectively, shown as supported by a bottom rack B which is fixed to the frame Z and from which the fingers 61, 61, 61, 61, project upwardly. From these rods, the sheets of threads T, T, T, T, pass through a leasing comb C of a well known type having dents or spacers such as 42 and 45 carried by a bottom frame 40 and a top or head 41. The dents 42 are plain or smooth on each side while the dents 45 have the downwardly projecting teeth 43 on each side as shown in Fig. 4.

By a well known method with top or head 41 removed, a single thread from each roll A is passed between each two dents, the parts being so positioned that in the beginning these threads are all below the teeth 43 as shown in Fig. 4.

In a well known manner, when a warp lifting lease rod such as R is raised and moved as to the left of Fig. 4, one thread 52 will continue going up while each adjoining thread 51 will be caught under a tooth 43. The rod and sheet are moved up and they or the comb can be moved to right or left.

The warp lifting lease rods R, R1, etc., need not be placed in the rack B but each can be pushed in from the side under a sheet of warp threads T and then raised and moved to the right or left with that sheet.

When the next sheet is lifted it is moved as to the right of Fig. 4 so that the next ends will be caught on the other side by a tooth 43 and the adjoining ones will continue up to the top. As this is repeated as to the left of Fig. 4 and as to the right of Fig. 4, it will be seen that there will be alternate threads positioned in the top part of a shed as compared with those in the bottom part and at that time a separating stick or rod such as N can be passed between them so as to retain the shed.

It is now necessary to reverse the threads by bringing the top ones below and the bottom ones above. Preferably I use outside the fixed rack B, a movable rack F, the side arms 63 of which are outside of the side arms 60 of rack B and its rod holding fingers. The rod holding fingers 61, on both sides of stationary rack B and 66 of movable rack F correspond with each other so that when rack F is moved down outside of rack B, the rods carried by it will be delivered into the fingers of rack B. Rack F can be moved from position F1 to F2 by manipulating the pairs of arms 1, 1, and 2, 2.

One end of each arm such as 1 is pivoted at

3 to the top of rack F and the other end at 4 is pivoted to the frame Z while each of the other pair of arms, such as 2, 2, is pivoted respectively at one end having a hole 26 to the bottom end of rack F on a pin 6 and the other end at 5 to frame Z.

For manipulating this top rack and moving it up and down, I show the hand operable pulley 8, with releasable locking means 9 and a turning wheel 90 around which is wound the lifting cord 7 which passes over a pulley such as L shown as fixed to the ceiling D and which extends down and its attached to a member 65 extending between and carrying the side arms 63, 63, of rack F. By turning this wheel 90, rack F can be lifted to F1 and locked in place by the device 9. When it is desired to lower rack F, means 9 is released and the pulley 8 is allowed to unwind the rope 7, thus dropping rack F into the position F2 from F1.

Referring to Figs. 1 and 2 when the movable rack F is in the raised position, shown in full lines by F1, it is ready to receive and hold, as they are lifted by hand, the rods R1, R2, R3, each carrying with it a sheet of warp threads T and when all the rods are so held and carried by rack F, it is lowered, as just described, to the F2 position shown by the dotted lines in Fig. 1 until the rods are stopped by the fingers 61, 61 of stationary rack B.

To entirely clear the fingers on rack F from the fingers on rack B, I find it convenient to release the bottom end of rack F from the bottom arms 2, 2, as shown in Fig. 2 allowing the top arms 1, 1, with movable rack F to be lifted up out of the way of the operators by turning wheel 90 to wind up rope 7.

Arms 2, 2, can now be raised and by engaging each hook 17 with a pin 6, each arm is held up out of the way.

As shown, the end of each arm such as 2 is preferably provided with a hole 26 to engage or disengage a pin pivot 6 so that they can be released allowing frame F to drop to the position F3 shown in Fig. 2.

H represents that part of the slasher which generally includes drying rolls such as 70 and K represents the warp beam which as shown is caused to revolve as by an electric motor 71 energized as by conductors 72 and 73 which are controlled by the shipper handle such as 10. Any mechanical or known device for stopping and starting the warp beam K can be used.

For convenience I have indicated the sheets of thread on and from each thread roll A by the letter T but after they have been separated to form a single shed or a double shed namely a lease, I have indicated them by W. The separating stick such as N, at a suitable time is replaced by a tape such as S as this allows the

leased warp to pass through the slasher and to be wound on the warp beam K without obstructing anything.

I claim:

- 5 1. The combination with a rayon slasher including a frame, drying rolls, a positively driven warp beam, means to so drive the warp beam including manually controllable means to stop and start it, a plurality of thread rolls, a brake for each thread roll, a leasing comb and a fixed lease rod rack attached to the frame and including two sloping arms each with a plurality of fingers for holding warp lifting lease rods; of a movable lease rod rack including two arms 10 each positioned outside the fixed lease rod rack arms and of substantially the same shape and slope and with fingers which substantially correspond with those on the fixed rack; two pairs of rack carrier arms, one end of each arm of each 15 pair being pivoted at one end to the top of the movable rack and the other end being pivoted to the frame, and one end of each arm of the second pair of arms being releasably pivoted to the bottom end of the movable rack and its other 20 end being pivoted to the frame at a distance from the pivot of the first carrier arm, the carrier arms being substantially parallel; and rack lifting means including a hand-operable pulley having releasable locking means, a lifting cord which 25 passes around such pulley and over another pulley above the movable rack and which connects with the movable rack whereby individual warp lifting lease rods can successively be raised and rested on the fingers of the movable lease 30 rod rack and that rack with all the lease rods can be lowered while the warp beam is turning and winding up the slack of the sheets of warp threads.

2. The combination with a rayon slasher including a frame, a positively driven warp beam, means to so drive the warp beam including manually controllable means to stop and start it, a plurality of thread rolls, a brake for each thread roll, a leasing comb lease rod rack attached to 40 the frame and including two sloping arms each with a plurality of fingers for holding warp lifting lease rods; of a movable lease rod rack including two arms each positioned outside the fixed lease rod rack arms and of substantially the same shape and slope and with fingers which substantially correspond with those on the fixed rack; and manually controllable means to raise and lower the movable rack whereby individual warp lifting lease rods can successively be 45 raised and rested on the fingers of the movable lease rod rack and that rack with all the lease rods can be lowered while the warp beam is turning and winding up the slack of the sheets of warp threads.
